UNITED STATES PATENT OFFICE

THOMAS G. HITT, OF SEATTLE, WASHINGTON

METHOD FOR FASTENING PYROTECHNIC ELEMENTS OR FIRECRACKERS TOGETHER

Application filed April 3, 1929. Serial No. 352,237.

This invention relates to improvements in packages and methods for detachably fastening a plurality of pyrotechnic display members or firecrackers together.

5 An object of this invention is to provide a means or method by which a plurality of firecrackers or other suitable elements may be detachably linked together, thereby providing a grouping of elements acceptable 10 and convenient for marketing.

A further object of this invention is to provide a bundle or plurality of firecrackers detachably linked together by means of their fuses, in such a manner that each element or 15 firecracker may be separated from the bundle without severing, cutting or breaking the fuses.

Other objects of this invention will appear 20 from the following detailed description and as disclosed in the single sheet of drawings which is herewith made a part of this application.

In the drawings—

Figure 1 illustrates a perspective view of a 25 bundle or plurality of firecrackers linked together, and disclosing one firecracker or element separated from the bundle.

Figure 2 illustrates a vertical sectional view 30 of a plurality of firecrackers, and the means by which they are detachably connected together, one of the firecrackers being in section for disclosing the explosive substance and chambers therein.

Figure 3 represents the top plan view of 35 Figure 2 disclosing the fuses interlinked together.

As one modification of this invention it is 40 preferred that numeral 1 designate a plurality of firecrackers detachably linked or connected together by means of fuses 2, which are made in loop formation, the free ends of the fuses 3 being adapted to extend a suitable distance within the firecracker 1 as clearly disclosed in Figure 2 of the drawings, where- 45 in numeral 4 designates a seal through which the fuse 2 extends into the firecracker, the loose ends of the fuses 2 being preferably twisted as disclosed in Figure 2 in order to form a more efficient anchoring within the 50 firecracker 1, the inner ends 3 of the fuses 2

are adapted to contact with an explosive substance consisting of some suitable explosive such as white powder 5 and brown powder 6.

In order to detachably fasten the plurality 55 of firecrackers or other elements 1 together it is preferred in this invention to assemble each firecracker as clearly disclosed in Figure 1, extending the loop to fuses 2 in series one through the other, in such a manner that the bundle or group of the firecrackers may be 60 easily disassembled by removing the loops one from the other as disclosed in Figure 1, and at the same time making it possible where desired to ignite the fuse at one end of the 65 assembled group, which would automatically function to ignite the fuses in each of the explosive elements thereby producing a pyrotechnic or explosive display of a plurality of firecrackers.

This invention provides very efficient means 70 or method for grouping a plurality of firecrackers or other suitable elements into a bundle, and in such a manner that each element may be separated from the bundle without 75 the cutting or the damaging of any portion of the connecting means, which in the preferred instance is the looped fuse of each explosive element.

A bundle of firecracker elements may be 80 assembled according to this invention of any desirable size and is extremely convenient for shipping for either wholesale or retail purposes.

The bundles of pyrotechnic display or firecrackers may be readily separated into their 85 single units for exploding purposes or retained in any plurality of groupings for the purpose of plural explosions.

As actually assembled, the fuse of the firecracker to be attached is inserted through the adjacent firecracker fuse loop. To do this 90 it is necessary that the firecracker be turned until the flat portion of the fuse loop will fit into the length of the fuse loop of the adjacent firecracker, after which the firecracker to be attached will be turned approximately forty-five degrees so that the length of the fuse loop will be in line with the adjacent loop, thus securely locking the same to the 95 adjacent firecracker. The usual procedure 100

is to bend the fuse loops over and flatten the same before interlocking; but the bending over step may be done, with the exception of the first firecracker on the string, after the fuse loop has been inserted through the adjacent fuse loop. The step of adding subsequent firecrackers is repeated until the desired number have been secured together.

This presents a very unique and superior means of the stringing and assembling of firecrackers.

When it is desired to remove one of the firecrackers, it is only necessary to turn the firecracker to be removed to an angle of forty-five degrees and then tilt the base of the firecracker upward, and at the same time, lowering the upper end so that the fuse loop will be pulled downwardly through the adjacent loop.

This method of securing the firecrackers together is a big improvement over methods heretofore used, as there is little danger of losing the fuses which commonly occurs in the ordinary method of securing the firecrackers together, and at the same time, a very attractive package is presented.

Having described my invention, what I claim as new and novel is:

1. A method for detachably connecting together a plurality of pyrotechnic display elements having looped fuses, consisting of connecting each pyrotechnic element together in series by linking the loops together.

2. A method for detachably connecting together a plurality of pyrotechnic display elements having looped fuses, consisting of connecting each pyrotechnic element by linking the loops together.

3. A method for detachably connecting a plurality of pyrotechnic display elements having looped fuses, consisting in connecting the elements together in series by passing the loops of each through the loop of the element preceding it in the series and bending each interlocked loop substantially at right angles to the axis of each element.

4. A method for detachably connecting a plurality of pyrotechnic display elements having looped fuses, consisting of turning the element to be attached to another element at substantially right angles to that other element, then inserting the loop of the first named element through the loop of the said other element and turning the attached element until its loop is substantially in line with that of the other element.

5. A package for pyrotechnic display elements comprising firecrackers having looped fuses, each of said firecrackers connected to the adjacent firecracker by means of said loop.

6. A package of pyrotechnic display elements comprising firecrackers having looped fuses, each of said looped fuses bent at substantially a right angle to the axis of the fire-

cracker containing said loop, each of said firecrackers connected to the adjacent firecracker by the interlocking of their loops.

7. A package of pyrotechnic display elements comprising firecrackers having looped fuses, said looped fuses bent at substantially a right angle to the axis of each element, said loops flattened to receive the loop of the adjacent firecracker.

8. A package of pyrotechnic display elements comprising firecrackers having looped fuses, each of said firecrackers connected to the adjacent firecracker by means of said loop, the length of the loop being greater than the width thereof.

In testimony whereof I affix my signature.

THOMAS G. HITT.
